(57) **CLAIM**

The ornamental design for a plastic container, as shown and described.

DESCRIPTION

FIG. 1 is a top-rear-right perspective view of the design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The dash-dash-dash-dash broken lines shown in the drawing views are for environmental purposes only and form no part of the claimed design.

The dot-dash-dot-dash broken lines shown in the drawings represent the boundary lines of the claimed design.
